ABSTRACT OF THE DISCLOSURE

A method of mechanical fractionation of gels is shown which includes the steps of applying pressure to the gel 15 while impinging the same upon a pressure responsive element in the direction of the pressure so as to divide the gel into fractions and applying a pressurized liquid to the pressure responsive area so as to carry away the fractions.

A mechanical fractionator for a gel is disclosed which includes a holding container to support the unfractured gel, a plunger within the container adapted to apply pressure upon the gel, a measuring mechanism for the pressure to be applied which includes a drive screw, a motor for driving the drive screw, a pressure responsive area adapted to receive the fractioned portions of the gel, and a conduit impinging upon the pressure responsive area adapted to contain a pressurized fluid so as to carry away the fractioned portions of the gel.

This invention relates to a method of mechanical fractionation of gels and one form of mechanical fractionator which can perform the same.

Substances distributed in gels including separated proteins, gels, in order to be properly studied, should be fractioned. Conventionally this has been done by various methods. The simplest is to hand section the gel. This, of course, is clumsy and bothersome. Electrophoresis has also been used to process the gel. This is expensive, requires highly sophisticated apparatus and is difficult to perform properly.

I have discovered a simple and inexpensive method to fraction gels involving the steps of applying pressure to the gel from one direction while impinging the gel upon an area responsive to the direction of the pressure and thence applying pressure fluid to the pressure responsive area so as to carry away the fractions. These fractions then can be placed into collecting containers and studied.

The above method can be most conveniently performed by the use of apparatus also described in the instant specification. The apparatus may be most broadly described as comprising a holding container adapted to support the gel, a pressure responsive area operatively connected with the container, a pressure producing mechanism selectively actuatable upon the gel disposed within the container, and carrier means operatively connected with the pressure responsive area.

The above constitutes a brief description of the instant invention and some of the objects and advantages thereof. Other objects and advantages of this invention will become obvious to the reader of this specification as the description proceeds.

The invention will be further described by reference to the accompanying drawings which are made a part of this specification.

FIG. 1 is a top view of the preferred form of apparatus for performing the mechanical fractionation of gels. In this view the apparatus is in horizontal position.

FIG. 2 is a side view of the apparatus shown in FIG. 1.

FIG. 3 is a fragmentary detail view of the apparatus shown in FIGS. 1 and 2.

2

FIG. 4 is a detail sectional view, on an enlarged scale of the pressure responsive area, the container and the pressure producing means and the carrier means of this invention.

FIG. 5 is a detail view partly in section, of the form of apparatus utilizing pressure fluid as the carrier means and also showing the manner in which the discharged gel fractions are collected. In this view the apparatus is in an inverted horizontal position.

FIG. 6 is a view identical to FIG. 5 but showing the gel fractions led into a different container.

FIG. 7 is a graph showing the results obtained by the use of the fractioning method of this invention.

FIG. 8 is a graph showing the results obtained by the conventional electrophoresis technique.

FIG. 9 is an enlarged detail cross-sectional view of a gel showing the various areas as they appear therein after staining.

The instant invention will now be further described by reference to the specific form thereof shown in the accompanying drawings. In this connection, however, the reader is cautioned to note that the specific form of the instant invention as set forth in the specification herein is for illustrative purposes and for purposes of example only. Various changes and modifications may obviously be made within the spirit and scope of this invention and would occur to those skilled in this art.

The mechanical fractionator 11 of this invention is formed with a holding container 12, a pressure responsive area 13 is operatively connected with container 12 and consists of a supporting member 14, a conduit (preferably vertical) 15 and a needle valve 16 disposed within conduit 15. Needle valve 16 comprises plunger 17, knob 18 and threaded stem 19 which in turn meshes with an additional threaded recess 20 provided within block 14. Support member 21 is also preferably provided which is formed with a threaded stem portion 22 which in turn meshes within an additional threaded recess 23 provided within block 14. Portion 21 surrounds container 12 and, in order to prevent leakage, an O-ring seal 24 is provided.

An additional conduit 25 (preferably at right angles to conduit 15) is also provided within block 14. Conduit 25 is joined to tubes 26 and 27. Tube 26 in turn passes through pump 28 and is joined to tube 29 which is disposed within a liquid (preferably water) 30 which is carried by flask 31. Conduit 27 may selectively be made to impinge upon collecting vessels 45, 46, 47, 48 and 49.

The gel to be fractionated 33 is formed into a plurality of stained areas 34 (FIGS. 5, 6 and 9).

The pressure producing mechanism preferably utilized in connection with this invention comprises a piston 35 which is adapted to move downwardly within container 12. The term "downwardly" relates to the direction of piston movement toward valve 16. Piston 35 is secured to drive block 36 which in turn moves downwardly on trunnions 37 and 38. Drive block 36 includes a threaded opening (not shown) through which drive screw 39 passes. Drive screw 39 has a measured thread thereupon and constitutes a measuring means for the movement of piston 35. Drive block 36 may be clamped into position by means of thumbscrew 40 which is provided with a stem 41 which in turn bears against member 39 through an opening within block 36.

Screw 39 is driven by reduction gear 42 which in turn is connected to gear 43 which is driven by motor 44. It is noted that piston 35 impinges upon an end portion of gel 33 and the opposite end portion of gel 33 impinges upon the pressure responsive area. Thus as piston 35 moves downwardly and the gel is fractionated the sequential integrity of the gel is maintained. That is, even though gel 33 is fractionated the sequence of the areas 34 within the unfractured gel also appears in the fractionated material

and each fraction is produced in the same sequence. This is very important for proper study of the gel material.

With the foregoing specific description, the operation of this invention may now be explained.

The gel to be mechanically fractionated 33 is placed within container 12 and piston 35 placed in a position above the gel. The piston is adjusted so that the lowermost portion of the gel impinges the uppermost portion of stem 17 (FIG. 6). The drive block 36 is then clamped into position and motor 44 actuated so that piston 35 is forced downwardly through container 12 and thereby applies a pressure to the gel 33 to be mechanically fractionated. At the same time, pump 28 is actuated forcing fluid 30 through conduits 29, 26 and 27 causing the pressure fluid to pass through the pressure responsive area and thus carry the crushed gel fractions into conduit 27 which in turn is placed into impingement with the collecting containers.

As seen by the showings in FIGS. 7 and 8, the result obtained by the method of this invention and by the use of the apparatus set forth therein are comparable to those obtained by conventional techniques.

The foregoing sets forth the manner in which the objects of this invention are achieved.

I claim:

1. A mechanical fractionator for a gel material comprising a holding container adapted to support said unfractioned gel material, a pressure responsive area operatively connected with said container and adapted to receive fractioned portions of said gel, a pressure producing mechanism selectively actuatable upon the gel disposed within said container to divide said gel into fractions, and carrier means including a pressurized liquid operatively connected with said pressure responsive area adapted to carry away the fractioned portions of said gel.

2. A mechanical fractionator as described in claim 1 wherein said pressure producing mechanism comprising a piston movable within said holding container and drive means operatively connected with said piston.

3. A mechanical fractionator as described in claim 1 wherein said carrier means comprise a first conduit in impinging relationship with said pressure responsive area, said conduit carrying said pressure liquid.

4. A mechanical fractionator as described in claim 3 wherein said pressure producing mechanism comprises a piston movable within said gel container in compressing relationship and motor means operatively connected with said piston to drive the same.

5. A mechanical fractionator as described in claim 4

including measuring means controlling the movement of said piston.

5 6. A mechanical fractionator as described in claim 5 wherein said pressure responsive area comprises a support, a substantially vertical second conduit within said support operatively connected with said holding container, said pressure liquid conduit being horizontally disposed and connected with said second conduit, and a needle valve within said support.

10 7. A mechanical fractionator as described in claim 6 said measuring means comprising a drive screw having measured threads thereupon.

8. A mechanical fractionator for a gel material comprising a holding container adapted to support unfractionated gel material having sequentially joined differing areas thereupon, a pressure responsive area operatively connected with said container and in impingement with an end portion of said gel, a pressure producing mechanism selectively actuatable upon the opposite end portion of the gel disposed within said container, said pressure producing mechanism and pressure responsive area adapted to fraction said gel but to maintain the sequential integrity thereof, and carrier means operatively connected with said pressure responsive area.

15 20 9. A method of mechanically fractionating a gel comprising the steps of applying pressure to the gel from one direction while simultaneously impinging said gel upon a pressure responsive element so as to divide said gel into fractions and applying a pressurized liquid to said pressure responsive area so as to carry away said fractions.

25 30 10. A method of mechanically fractionating a gel formed with a plurality of differing areas within said gel but without destroying the sequential integrity thereof comprising the steps of placing said gel within a holding element and applying pressure to the gel from one direction while simultaneously impinging said gel upon a pressure responsive element so as to divide said gel into fractions, and thence applying carrying means to said pressure responsive area.
